BLAST MACHINE SYSTEM AND METHOD
Ardee H. Freeman, Granger, and Frederick J. Pichard,
South Bend, Ind., assignors to Bell Intercontinental Cor-
poration, South Bend, Ind.

Filed May 11, 1962, Ser. No. 194,019
6 Claims. (Cl. 51-13)

This invention relates to blast machine systems such as are used to clean up castings or other semi-finished workpieces, and more particularly to an improved system having an alternative blast media cycling arrangement whereby contaminant accumulations may be from time to time purged from the system, such as after each heavy sand loading cycle of operation thereof. In consequence the blast machine may be at all times more efficiently employed to perform on castings or other workpieces, rough cleaning and finish clean-up processes.

Previously, because of the greatly variable sand loads incident for example to core knockout and rough cleaning and finish-cleaning operations, shot blast machine systems have been found prone to accumulating at various stations therein concentrations of harmful percentages of sand and debris contents, which accumulations on occasion dislodge and then flood the blast machine with intolerable surges of debris. Such tendency invariably exists for example in the feed hopper located just above the blast machine feed inlet.

The present invention contemplates, in a blast machine system, means for selectively "dumping" such accumulations through a by-pass conduit to an intermediate storage hopper and thence to the system separator, thereby bypassing the blast machine and protecting the latter from undue wear and otherwise inefficient operation. It is well known that only slight increases of sand percentages in the spent shot and sand mixture will cause tremendous wear of the blast machine centrifugal wheel and liners etc., as well as reducing the blasting efficiency of the machine.

Thus, a primary object of the present invention is to provide in a blast machine system, means for efficiently bypassing contaminant accumulations and recycling them to the system separator, whereby to reduce the blast machine wear maintenance problems. Other objects and advantages of the system of the invention will be apparent from the specification hereinafter having reference to the accompanying drawing wherein:

FIG. 1 is a somewhat schematic elevational view of one form of system of the invention; and

FIG. 2 is a fragmentary sectional view through a feed hopper component of the system, illustrating undesirable accumulations therein.

As shown in the drawing, a blast machine system embodying the invention may comprise generally a tumble blast unit 10 including a cradle type conveyor 12 of table or the like which supports and tumbles a load of castings which are to be processed, such as are indicated at 15. A shot throwing machine as indicated at 16 is disposed above the load of castings and operates to sling shot or loose abrasive material against the workpieces, as is well known in the art. With a view to simplification of this specification the tumble blast and abrasive throwing machine components will not be illustrated and described in further detail; the details of construction and operation of typical examples thereof being fully disclosed and explained in U.S. Patents 2,104,055 and 2,819,562. However, it is to be understood that in lieu of the specific forms of workpiece supporting and tumbling and shot throwing devices illustrated herein and disclosed in the referenced patents, any other suitable forms of equipment may be employed, such as for example swing table machines as disclosed in U.S. patent application S.N.

2

14,903, filed March 14, 1960, by Alfred Schnetzer, now Patent No. 3,041,786. The hopper and feed chute for supplying abrasive to the unit 16 are indicated at 18 and 20, respectively, and the conveyor for carrying away spent abrasive and debris is indicated at 22.

In any case the blast machine is coupled into an abrasive and debris circulating and separation system such as may include the conveyor 22 shown as discharging the debris an an abrasive mixture from machine 10 to the foot of an elevator 24. Elevator 24 delivers to a cross conveyor 26 which delivers into a separator 28. The construction and operation of a separator suitable for this purpose is shown and described in full detail for example in pending U.S. patent application Serial No. 831,525, filed August 4, 1959. The separator includes a sand or "refuse" discharge spout 30 delivering into any suitable take-away device, and the cleaned abrasive from the separator delivers into the hopper 18. A control valve as shown at 38 is disposed in the feed line to the abrasive throwing machine 16.

After each batch of castings or the like is loaded by any suitable means into the blast machine the door of the machine is then closed and the castings are tumbled and/or turned while the unit 16 is activated with the valve 38 open so that the blast operation dislodges sand and/or surface scale or other debris from the workpieces. During this process the contaminated abrasive cycles through the separator so that the dislodged sand and scale and worn out blast media may be discarded from the system through the outlet 30. However, the hopper 18 may from time to time be found to have acquired a thick lining of high percentage debris content as indicated at 50 (FIG. 2) through the center of which the still circulating stream of cleaned blast media material flows. Unless such accretions are removed from the system they will from time to time dislodge and flood the blast machine with surges of debris, thereby rendering the machine operation for some time ineffective. Also, this will impose undue wear upon the blast machine parts.

To avoid the difficulties and disadvantages referred to, we provide a separate bypass conduit or conveyor as indicated at 40 to permit periodic "dumping" of the entire contents of the hopper 18. The chute 40 leads to a hopper 42 leading to the elevator 24, which in turn leads to the separator 28; the chute 40 being controlled by a valve 44. Thus, with the valve 44 opened and the valve 38 closed, the abrasive-debris mixture in the hopper 18 is completely dumped to hopper 42. The valve 44 is then closed. The mixture in 42 is then metered back into the system through valve 46 at a rate consistent with the capacity of the separator; the separator functioning to discard from the system the worn-out blast media and fine debris from the mixture. When hopper 42 is emptied hopper 18 will contain only clean blast abrasive whereupon the system is realigned for normal operation as explained hereinabove. This cleaning out cycle may be repeated if necessary.

Thus, it will be appreciated that the present invention provides an improved machine organization, the components of which are at all times in use at their peaks of efficiency; and that control of the cleaning out process as outlined above may be performed either manually or automatically or semi-automatically as preferred, to adapt the system for example to series operations on like workpieces. Also, that although only one form of the invention has been illustrated and described in detail hereinabove, it will be understood that various changes may be made therein without departing from the spirit of the invention or the scope of the following claims.

We claim:

1. A unit machine system for blast-cleaning workpieces, said machine system including a workpiece receiving de-

3

device adapted to turn the workpiece, a blast machine arranged to bombard the workpiece as it is turned, a feed hopper delivering blast media to said blast machine, a separator receiving contaminated blast media residual to the blasting operation, said separator having a debris discharge and a reusable blast media discharge separate therefrom, and a reusable blast media discharge delivering to said feed hopper, a by-pass conveyor returning from said feed hopper to an intermediate storage hopper arranged to discharge to said separator intake, a first valve controlling passage through said by-pass conveyor, a second valve controlling passage from said storage hopper to said separator, a third valve controlling passage to said blast machine, said valves being selectively actuatable so as to either block passage of blast media through said blast machine while causing circulation of all material in the system through said separator, or to cause recycling of the reusable blast media through said feeder hopper and said blast machine against said workpieces.

2. A unit machine system for blast-cleaning workpieces, said machine system including a workpiece receiving device adapted to turn the workpiece, a blast machine arranged to bombard the workpiece as it is turned, a feed hopper delivering blast media to said blast machine, a separator receiving contaminated blast media residual to the blasting operation, said separator having a debris discharge and a reusable blast media discharge separate therefrom, said reusable blast media discharge delivering to said feed hopper, a bypass conveyor returning from said feed hopper to an intermediate storage hopper arranged to discharge to said separator intake, a first valve controlling passage through said bypass conveyor, a second valve controlling passage from said storage hopper to said separator, a third valve controlling passage to said blast machine, said valves being selectively actuatable.

3. A unit machine for cleaning out cores and heavy surface debris from castings and then finish-cleaning the same, said machine comprising, a casting receiving device adapted to turn the castings, an airless blast device arranged to throw loose blast media at the castings as they are turned, a feeder delivering media to said blast device, a separator receiving debris and spent media falling away from said castings, said separator having a debris discharge and a reusable media discharge separate therefrom, said reusable media discharge delivering to a hopper above said feeder, a bypass conduit interconnecting said hopper and said separator intake, a first valve controlling passage through said bypass conduit, a second valve controlling passage through said feeder, and control means operative to alternatively set said valves so as to block passage of blast media through said feeder while circulating all material falling away from said castings through said separator and alternatively cycling the reusable media therefrom through said feeder and said blast device against said castings.

4. A unit machine for sequentially knocking out hard to dislodge cores from castings and then finish-cleaning the same, said machine comprising, a casting receiving device

adapted to tumble the castings, a blast device arranged to throw blast media at the castings as they are tumbled, a feeder delivering blast media to said blast device, a separator receiving debris and spent media falling away from said castings, said separator having a debris discharge and a reusable media discharge separate therefrom, said reusable media discharge normally delivering to said feeder, a bypass conveyor returning from said media discharge to said separator intake, a first valve controlling passage through said bypass conveyor, a second valve controlling passage through said feeder, and control means operable to sequentially control said valves so as to initially block passage of media through said feeder while circulating all material falling away from said casting through said separator and subsequently cycling the reusable media therefrom through said feeder and said blast device against said casting.

5. A unit machine for cleaning out cores and heavy surface debris from castings, said machine comprising, a casting receiving device adapted to tumble the castings, an airless blast device arranged to throw loose blast media at the castings as they are tumbled, a feeder delivering media to said blast device, a separator receiving debris and spent media falling away from said castings, said separator having a debris discharge and a reusable media discharge separate therefrom, said reusable media discharge delivering to a hopper above said feeder, a bypass conduit leading away from the bottom of said hopper and a valve controlling passage through said by-pass conduit and operable so as to initially block passage of material through said bypass conduit while circulating all material falling away from said castings through said separator and subsequently cycling the reusable media therefrom through said feeder and said blast device against said castings.

20 6. A method of cleaning castings and for segregating usable blast media and debris from a system including a blast machine operating on castings and a hopper feeding and said machine with blast media, which method comprises placing a casting requiring to be cleaned on a support arranged to turn said casting for shaking out the foundry core material and other loose debris while conveying said debris to a separator having a debris discharge and a cleaned blast media discharge delivering to said hopper, then shot-blasting said casting while it is being tumbled to remove residual core and surface material and delivering the spent shot and debris materials to said separator while periodically bypassing the accumulations within said hopper back to said separator, whereby accumulations of fine debris in said hopper may be periodically dumped 25 30 35 40 45 50 to purge the system thereof.
